William Marshall

UNITED STATES PATENT OFFICE.

CARL O. JOHNSON, OF MINNEAPOLIS, MINNESOTA.

TOBACCO PIPE.

Application filed May 17, 1920. Serial No. 381,821.

To all whom it may concern:

Be it known that I, CARL O. JOHNSON, a citizen of the United States, residing at Minneapolis, in the county of Hennepin and State of Minnesota, have invented certain new and useful Improvements in Tobacco Pipes; and I do hereby declare the following to be a full, clear, and exact description of the invention, such as will enable others skilled in the art to which it appertains to make and use the same.

My invention has for its object to provide an improved tobacco pipe, and to this end, the invention consists of the novel devices and combinations of devices herein-after described and defined in the claim.

In the accompanying drawings, which illustrate the invention, like characters indicate like parts throughout the several views.

Referring to the drawings:

Fig. 1 is a side elevation of the improved tobacco pipe;

Fig. 2 is a view principally in longitudinal central section; and

Fig. 3 is a plan view of one of the absorbent partitions.

My improved tobacco pipe may take various different forms and, as illustrated, comprises a bowl 4, a sub-bowl 5, a straight stem 6 and a straight mouth piece 7. In the bottom of the bowl 4 are a plurality of smoke passageways 8, and the extreme lower end of said bowl is reduced and detachably screwed into the sub-bowl 5. In the bottom of the sub-bowl 5 is a smoke chamber 9, and formed thereabove, in the internal wall of said sub-bowl, are two vertically spaced annular shoulders or shelves 10, on which are removably seated two disk-like partitions 11 of cotton or other absorbent material. These partitions 11 are vertically spaced by the shoulder 10 to afford an air space 12 therebetween and act as smoke purifiers.

The marginal edges of the partitions 11, as shown, are re-inforced by attaching thereto rings of paper or other suitable material 13, but these are not necessary and may be dispensed with. The stem 6 and mouth piece 7 are detachably connected internally by a screw-threaded sleeve 14 on the outer end of a smoke conduit 15 of aluminum or other suitable material. The outer end of the smoke conduit 15 is inserted through a bore 16 in the sub-bowl 5 and connects the

smoke chamber 9 with a saliva chamber 17 in the inner end of the mouth piece 7. As shown, the stem 6 is integrally formed with the sub-bowl 5 and is provided with an air chamber 18, which surrounds the smoke conduit 15.

Intake and outlet passageways 19 and 20 connect the air chamber 18 to the atmosphere, and it will be noted that these passageways are located in the vicinity of the outer and inner ends of said air chamber, respectively. An axial passageway 21 in the mouth piece 7 extends from the inner end of said mouth piece to the mixing chamber 17.

The purpose of the smoke purifying partitions 11 is to absorb the greater part of the nicotine and moisture in the smoke during its travel from the bowl 4 to the smoke chamber 9, thereby leaving the smoke milder and prevents the pipe from becoming foul. When the partition plates 11 are filled up, they may be removed and new ones substituted therefor. The intake and outlet passageways 19 and 20 afford a circulation of air through the air chamber 18 and around the smoke conduit 15 to keep said air conduit cool and, hence, cool the smoke in its travel from the smoke chamber 9 to the saliva chamber 17. To remove the partitions 11, it is only necessary to unscrew the bowl 4 from the sub-bowl 5 and when said partitions are removed, the smoke chamber 9 may be easily cleaned. By unscrewing the mouth piece 7 from the sleeve 14 and then unscrewing said sleeve from the stem 6 to remove the smoke conduit 15 from said stem, said mouth piece and smoke conduit may be easily cleaned.

What I claim is:

A tobacco pipe comprising a stem having two distinct longitudinal chambers formed therein, the inner of which forms a saliva collecting chamber and the other of which forms a cooling chamber, said cooling chamber having an aperture therefrom to the atmosphere at its top portion adjacent one end and another aperture to the atmosphere at its bottom and adjacent its other end, a conduit passing centrally through said cooling chamber and communicating with said saliva collecting chamber, said stem having a sub-bowl with a chamber formed therein at its outer end with which chamber the other end of said conduit com-

municates, a tobacco receiving bowl attached to said stem above said sub-bowl having a perforated bottom, and a plurality of spaced layers of absorbent material disposed in said sub-bowl chamber and spaced from said perforated bottom of the tobacco receiving bowl.

In testimony whereof I affix my signature in presence of two witnesses.

CARL O. JOHNSON.

Witnesses:

FRED CARLSON,
AXEL SCOBLOM.
